THOMAS S. PATTERSON, OF MALAGA, NEW JERSEY, AND PETER G. PRITZ, OF GERMANTOWN, PENNSYLVANIA, ASSIGNEES OF ONE-THIRD TO JAMES J. PRITZ, OF PHILADELPHIA, PENNSYLVANIA

BEVERAGE MIXER AND DISPENSER

Application filed September 15, 1928. Serial No. 306,240.

The object of the invention is to provide improvements broadly in beverage dispensing means, such as are automatically controlled by the use of a coin of predetermined size or denomination, and which dispensing means is wholly independent of any outside agency for its complete operation after being properly supplied with the ingredients of which the beverage or beverages are composed.

More particularly the invention provides for the proper measuring of definite quantities of any desired syrup with such a fluid as carbonated water under pressure, said syrup and fluid being mixed and dispensed into a suitable container such as a paper cup, which cup has been released from a magazine, and which cup when filled with a predetermined quantity operates to release a door or other element, which until a given point in the operation of the device bars access to its interior.

Another object is to provide an ingenious arrangement of suitable mechanism, whereby the pressure from within the well-known carbonated water or other tank serves as the actuating means for the complete operation of the said mechanism, upon its release by the application of the coin above referred to, said pressure no matter what it may be within the tank being reduced to any desired operating pressure, and being operative after the completion of the cycle of movements to reset the mechanism so as to respond immediately upon the application of a second coin, and so on until the tank is devoid of its fluid contents.

Further objects consist in providing novel means for the rejection by the device of any undersized coin, that is for instance a cent or dime when the proper operating coin is a nickel; in providing novel means for the release of a cup from its magazine into operative position by and during the operation of the fluid controlling mechanism; in providing door release latch mechanism actuated by the cup upon becoming properly filled; in providing suitable refrigerating means for cooling the syrup and carbonated water; in providing novel means for measuring first

the syrup and then the water, through a common valve; and in providing numerous other details of construction and operation as brought out in the following description, when read in conjunction with the accompanying drawings in which Fig. 1 is a vertical section taken through one embodiment of the invention and more particularly on the line 1—1 of Fig. 2; Fig. 2 is a section on the line 2—2 of Fig. 1; Fig. 3 is a section on the line 3—3 of Fig. 1; Fig. 4 is a section on the line 4—4 of Fig. 1; Fig. 5 is a section on the line 5—5 of Fig. 1; Fig. 6 is a section on the line 6—6 of Fig. 1; and Figs. 7 and 8 comprise sections through a part of the operating portions of the device with the respective elements embodied therein shown in different positions corresponding with different phases in the operation of the mixing and dispensing mechanism.

Referring to the drawings, an outside cabinet may be made of any suitable shape, but in the present instance comprises a front wall 1, having an aperture 2, normally closed by means of a door comprising a frame 3 surrounding a preferably transparent panel 4, said door being held normally in closed position by means of a latch comprising an arm 5 which is carried by one end of a rod 6, the central portion 7 of which is curved in a substantially semi-circular shape and adapted to support a cup or other vessel 8 into which a beverage is dispensed and from which it is drunk by the patron or purchaser, the opposite end portions of the rod 6 being journaled in opposite portions of a transversely U-shaped casing 9, having an open side which registers with the opening 2 in the cabinet wall 1 and a closed bottom 9'. This same front wall 1 is also preferably provided with an aperture 10 through which used cups are thrust after serving the function for which they are designed, an L-shaped tube 11 being secured to said front wall in communication with the aperture 10 and being directed inwardly and downwardly so as to discharge the used cups into a waste container 12, removably positioned within the cabinet and resting upon the lowermost wall 13 of the latter. It will also be noted that a drain 100

tube 14 leads from the lowermost portion of the cup surrounding casing 9 towards and so to direct liquid which may spill within said casing into said waste container.

Preferably, in the upper portion of the cabinet and adjacent to the rear wall 15 is a compartment surrounded by heat insulation material 16 and divided into two sections 17 and 18 for the respective cooling of the carbonated water or other diluting agent and the syrup or other base from which the beverage is formed. The heat insulating material 16 may be of any suitable type such for instance as cork, mineral wool, or the like, and it is confined between the rear wall 15 and the wall 19 of a shell which also comprises end walls 20 in spaced relation with the parallel side walls 21 of the cabinet and an irregular inwardly positioned wall 22 in spaced relation with a correspondingly shaped wall 23, extending across the interior of said cabinet between the sides 21 of the latter, substantially as shown in horizontal section in Fig. 2. Access to the compartment sections 17 and 18 may be gained through one or more double walled closures 24, including a layer of heat insulating material 25. The lower portion of these compartment sections is closed by means of a double walled bottom 26 also embodying a layer of heat insulating material 27.

Within the cabinet thus described, there is positioned adjacent to the front wall 1 and above the aperture 2, any suitable form of cup magazine 28, adapted to support reserve cups 29 from which the lowermost cup 30 drops into the position shown in Figs. 1, 2, 3 and 6 by any suitable type of release mechanism actuated by a lever 31, connected by means of a chain 32 over a pulley 33 with variable positions 34 upon an actuating lever 35, pivotally carried at 36 by a block 37 secured within and by the adjacent walls of the cabinet and actuated as hereinafter described.

Opening through any suitable portion of the front wall 1 is the receiving end 38 of a coin chute 39, which is provided at any suitable point with a laterally curved portion 40, having a laterally disposed elongated opening 41 adapted to permit coins of sizes smaller than that for which the apparatus is designed to operate to fall from said chute into any desired position or receptacle, whence they can be removed by the one operating the device. On the other hand, coins of the proper size or denomination continue downwardly through said chute until they pass therethrough and into any suitable form of receptacle from which they too can be removed by the owners or lessors of the device, after such coins have actuated the arm 42 of a lever which is pivotally supported at 43 by any suitable medium, and also comprises a second arm 44 having a cutaway portion 45 providing a shoulder 45, said lever being

yieldingly maintained in its normal position with the first arm 42 in raised elevation by means of a spring 46, the tension of which is adjustable in any suitable manner as for instance by means of the set screw 47.

Pivoted at 48 is a lever having an arm 49 which normally engages said shoulder 45, and a second arm having an angular shape so as to provide a seat 50, in and against which rests a link 51 through the medium of an anti-friction roller 52. The lever arm 49 is yieldingly maintained in its normal position by means of spring 53, while the link 51 is maintained in extended relation with respect to the arm 54 of a lever by which it is pivotally supported at 55 by means of a spring 56, carried by said last-named lever.

The lever arm 54 extends beyond a supporting pivot 57 and is integral with an oppositely extending arm 58, terminating in a flattened extension 59, through which extends an aperture 60 for a purpose hereinafter described. The arm 54 of this last-mentioned lever is provided with an L-shaped rest 61, upon which the lower free end portion of a rod 62 is adapted to move, but is prevented from moving beyond said rest in one direction by a wall 63, the longitudinal movement of said rod 62 being freely permitted, while its transverse movement is relatively limited by a bracket 64 through an aperture in which said rod slidably extends. Also, the lower portion of said rod is yieldingly positioned adjacent to the rest 61 by means of a spring 65 carried by the lever arm 54, the arrangement being such that when said lever arm is depressed, the lower free end of the rod 62 rides relatively upwardly and over the rest 61 so that the rod is moved upwardly as the lever arm moves in that direction, said rod, however, at a predetermined point in its upward movement being removed from engagement with the rest 61 as said rod engages one side of the aperture 64' in the bracket 64 through which it extends.

The oppositely extending lever arm 58 is provided with a laterally extending pin 66 which is adapted to be engaged by a shoulder 67 of a notched portion of a lever arm 68, pivotally supported at 69, and provided with oppositely extending flattened and weighted portions 70 and 71 respectively, said flattened portion being in alignment with the aperture 60 in the flattened portion 59 of the lever arm 58 and in spaced relation therewith. Said lever arm 58 is also connected adjustably with the lower end portion of a rod 72, while upon its flattened portion 59 and in axial alignment with the aperture 60 is a spiral compression spring 73, through which slidably extends a link 74 carrying an adjustably positioned nut or stop 75, and supported by the lower end portion of a piston rod 76.

The lower exposed portion of the piston rod

76 is provided with a laterally projecting arm 77 in alignment with and adapted to engage the actuating lever 35 to trip the latter and release the cup 30 from the magazine 28 at a predetermined point in the operation of the device. Said piston rod is also provided with a laterally extending arm 78, said last-named arm as the piston rod rises being adapted to engage the diagonally directed free end portion 79 of a rod 80 which, at a suitable locality, is provided with an elongated slot 81 through which slidably extends a pin 82 by which said rod is carried by a bracket 83, the uppermost free end portion of said last-named rod being diagonally directed at 84 to form a lug adapted to engage the shoulder 85 of a reciprocator rod 86, which in turn is connected to the stem 87 of a normally closed valve 88. The piston rod 76 passes into a cylinder 89 through a head 90 and is provided with a piston 91, which with said piston rod is normally maintained in its uppermost position against the stop 92 by means of a spiral compression spring 93 surrounding said last-named rod within said cylinder. The upper portion of said cylinder extends beyond the stop pin 92 and terminates in a closed end 94, provided with an air escape orifice 95, adapted to be closed normally by a suitable closure 96, carried by a float 97, while the sides of said cylinder are provided with apertures connecting with inlet and outlet tubes 98 and 99, respectively, preferably a slight distance above the uppermost limit of movement of the piston 91.

Within the cabinet is removably positioned any well-known type of tank 100 which is normally connected at 101 to one end of a coil of pipe 102, positioned within the cooling compartment section 17, said coil communicating through a pressure-reducing valve 103 with a pipe 104, which leads through a normally closed valve 105, through a pipe 106, to a T coupling 107 of a special construction, the valve 105 being normally closed by means of a valve actuating stem 108, which is engaged by a suitably mounted bell crank lever 109, which latter at its free end is connected with the rod 72, in turn adjustably connected at its lower end 72' with the lever arm 58.

Within the second cooling compartment section 18 is positioned a syrup tank, from which leads a pipe 110, which communicates through a normally open valve 111 and through a pipe 112 with that end of the T coupling 107 opposite to the pipe 106, said T being connected with the interior of the upper portion of the cylinder 89 through the pipe 112 above referred to. Within said T there is positioned a ball valve 113, which, when the valve 111 is open, is adapted to close the entrance to said T from the pipe 106 and thus prevent syrup from flowing into said last-named pipe instead of pass-

ing through said T and laterally therefrom into the cylinder 89. On the other hand, at a later time in the operating cycle of the device, when the valve 111 is closed and the valve 105 is open, the pressure in the pipe 106 is operative to force said ball valve 113 upwardly so as to prevent the water within the pipe 106 under pressure from passing upwardly into the syrup supply pipe 110, but instead directing said water laterally into the cylinder 89.

The valve 111 is provided with a valve stem 114 which is operated by a lever 115, having its outer end connected by a spring 116 to one end of a lever 117, in turn pivotally supported at 118 upon the bracket 83, the opposite free end of said last-named lever being adjustably connected with the rod 62. The rod 80 also supported by said bracket is normally held laterally outwardly by means of a spring 119 in such manner that as said rod 80 is raised, its offset 84 engages the shoulder 85 above referred to. It will also be noted that the lever 117 is yieldingly maintained in a predetermined position by means of a spring 120 connected with any suitable fixed point, and which last-named spring is of a different degree of tension than the spring 116, extending between the lever 117 and the valve stem actuating lever 115 of the valve 111.

In the operation of this device, the respective elements as shown in Fig. 1 are in a position of rest and are set for the complete operation of the device. The pressure in the tank 100, when the latter is filled, is one hundred and fifty (150) pounds to the square inch or thereabouts, though the effective pressure in the pipe 104 is reduced by the valve 103 to any desired extent as for instance to sixty (60) pounds to the square inch. Ice or other suitable refrigerating medium is placed within the compartment section 17 so as to chill the coil 102, valve 103, and adjacent syrup tank in the compartment section 18. The cup 8 is not in position, though it is shown in dotted lines, but instead comprises the lowermost cup 30 suspended by and from the magazine 28. The valve positions are as shown in Fig. 7 and the syrup by gravity is assumed to have passed through the pipe 110, valve 111, pipe 112, and T 107 into the upper portion of the cylinder 89 above the piston 91 in its uppermost position, until the float 97 has risen sufficiently to close the air escape aperture 95 and thereby prevent further syrup from entering said cylinder.

A coin of proper denomination, as for instance a five cent piece, is inserted into the receiving end 38 of the coin chute 39, said coin in passing downwardly finally dropping upon the lever arm 42 which it trips, with the result that the lever arm 49 is released by the shoulder 45 and the link 51 drops, permitting the lever arm 54 to drop, and raising

the lever arm 58 upwardly. The lower end of the rod 62 is thereupon received by the rest 61 and the pin 66 engages the shoulder 67 of the lever arm 68, the weighted arm 71 having simultaneously raised the flattened portion 70 of said last-named lever. The upward movement of the lever arm 58 raises the rod 72 and thus opens the water supply valve 105, raising the ball 113 to close the syrup entrance 112' at the upper end of the T 107. The pressure of sixty pounds or thereabouts within the line 104-106, forces the piston 91 downwardly to the position shown in Fig. 8, the piston supported arm 77 engaging the lever 35, which, through the chain 32, operates the lever 31 to release the cup 30 to drop into the position 8 supported by the centrally curved portion 7 of the latch rod 6. The nut or stop 75 carried by the link 74 engages the spring 73 as the piston rod moves downwardly, thus storing pressure through the compression of said last-named spring and finally passes and extends through the aperture 60 in the lever arm 58 and engages the flattened portion 70 of the lever therebeneath, with the result that the shoulder 67 becomes disengaged from the pin 66, whereupon the compression of the spring 73 forces the lever 58 suddenly downwardly, so that the upward movement of rest 61 forces the rod 62 upwardly, tilts the lever 117 tensioning the spring 116 and closing the valve 111. Also, the lever arm 58 in lowering depresses the rod 72 and closes the valve 105, thereby stopping the inflow of the diluent such as carbonated water, or other liquid, under pressure, through the T 107 and into said cylinder 89.

The lever 117 also lowers the rod 86 and opens the valve 88, thus permitting the combined charge of water and syrup within the cylinder 89 to be ejected by the piston 91 under pressure of the spring 93 into the swirl cup 121, whence the mixed fluids pass by gravity through a discharge pipe 122 into the cup 8. The lever 117 in lowering the rod 86 permits the shoulder 85 to be engaged by the notched end 84 of the rod 80, thereby holding the valve 88 open until the beverage is delivered to the cup. The piston rod 91 in rising carried the projecting arm 78 upwardly and thereby, upon the ejection of the beverage, engages the end portion 79 of the rod 80, which releases the shoulder 85 and permits the valve 88 to close. This movement also permits the valve 111 to open and pass a second charge of syrup into the cylinder 89, the air therein escaping through the port 95, as the float, upon the cessation of the upward movement of the piston 91, drops with the outflow of the syrup upon the stop pin 92. Also with the reopening of the syrup valve 111, the ball 113 drops to its lower seat and permits the syrup to flow into said cylinder until again arrested by the float closing the port 95.

As before mentioned, when a predetermined quantity of beverage has entered the cup 8, its weight tilts the rod 6 so as to raise the arm 5 free from engagement with the door frame 3, after which the purchaser is free to open the door and remove the filled cup from its rack. The door 3-4 is preferably returned automatically by a spring-hinge 123, or the like, to its closed position and after one has consumed the contents of the cup 8, the latter may be deposited through the cabinet aperture 10 and tube 11 into the waste receptacle 12. This operation may obviously then be repeated as many times and as frequently as desired and until the supply of syrup and carbonated water or other diluent have been exhausted, after which they may be replaced and the operation of the device proceeded with as before described.

Having thus described our invention, what we claim and desire to protect by Letters Patent of the United States is:—

1. A beverage mixing device, comprising a mixing chamber, means to convey a syrup to said chamber, means to limit the quantity of syrup admitted thereto, means to convey a diluent under pressure into said chamber, means to limit the quantity of diluent admitted thereto, a valve to permit the flow of the mixed syrup and diluent from said chamber, and means actuated by the pressure upon the diluent whereby operation of said valve permits said last-named means to force the contents from said chamber.

2. A beverage mixing device, comprising a mixing chamber, means to convey a syrup to said chamber, means to limit the quantity of syrup admitted thereto, means to convey a diluent under pressure into said chamber, means to limit the quantity of diluent admitted thereto, a valve to permit the flow of the mixed syrup and diluent from said chamber, and a yieldingly positioned piston within said chamber displaced by the pressure upon said diluent, and operative upon the release of said valve to permit said piston to eject the contents of said chamber.

3. A beverage mixing device, comprising a mixing chamber, a pressure piston therein, means to normally position said piston at an innermost limit, a valve having branches and connected with the interior of said chamber, a conduit connecting a branch of said valve with a source of syrup, a conduit connecting another branch of said valve with a source of diluent under pressure, a normally open valve in the syrup conduit and a normally closed valve in the diluent conduit, means in said first-named valve to prevent the flow of syrup into said diluent conduit while flowing into said chamber, and to prevent the flow of said diluent into said syrup conduit while flowing into said chamber, means to limit the flow of syrup to a predetermined quantity within said chamber, and a valve to release

and permit the expulsion of said syrup and diluent, said piston being moved by the pressure upon the diluent and operative to force the mixed syrup and diluent from said chamber when the pressure therein is released.

4. A beverage mixing device, comprising a mixing chamber, a pressure piston therein, means to normally position said piston at an innermost limit, a valve having branches and connected with the interior of said chamber, a conduit connecting a branch of said valve with a source of syrup, a conduit connecting another branch of said valve with a source of diluent under pressure, a normally open control valve in the syrup conduit and a normally closed control valve in the diluent conduit, coin-actuated means to regulate said control valves at predetermined intervals in sequence, means in said first-named valve to seal said diluent conduit when said syrup conduit is connected with the interior of said chamber, and to seal said syrup conduit when said diluent conduit is connected with the interior of said chamber, a float within said chamber to close said aperture and limit the quantity of syrup in said chamber, and a valve also coin-actuated to release and permit the expulsion of said syrup and diluent, said piston being moved against the tension of said spring by the pressure upon said diluent, and operative to force the mixed syrup and diluent from said chamber upon the release of pressure therein.

5. A beverage mixing device, comprising a mixing chamber having an aperture, a piston therein, a coil spring to normally maintain said piston in its innermost position, a valve having branches and connected with the interior of said chamber, a conduit connecting a branch of said valve with a source of syrup, a conduit connecting another branch of said valve with a source of diluent under pressure, a normally open valve in the syrup conduit and a normally closed valve in the diluent conduit, means in said first-named valve to seal said diluent conduit when said syrup conduit is connected with the interior of said chamber, and to seal said syrup conduit when said diluent conduit is connected with the interior of said chamber, a float within said chamber to close said aperture and limit the quantity of syrup in said chamber, and a valve to release and permit the expulsion of said syrup and diluent, said piston being moved against the tension of said spring by the pressure upon said diluent, and operative to force the mixed syrup and diluent from said chamber upon the release of pressure therein.

6. A beverage mixing device, comprising a mixing chamber having an aperture, a piston therein, a coil spring to normally maintain said piston in its innermost position, a valve having branches and connected with the interior of said chamber, a conduit connecting a branch of said valve with a source of syrup, a conduit connecting another branch of said valve with a source

branch of said valve with a source of diluent under pressure, a normally open control valve in the syrup conduit and a normally closed control valve in the diluent conduit, coin-actuated means to regulate said control valves at predetermined intervals in sequence, means in said first-named valve to seal said diluent conduit when said syrup conduit is connected with the interior of said chamber, and to seal said syrup conduit when said diluent conduit is connected with the interior of said chamber, a float within said chamber to close said aperture and limit the quantity of syrup in said chamber, and a valve also coin-actuated to release and permit the expulsion of said syrup and diluent, said piston being moved against the tension of said spring by the pressure upon said diluent, and operative to force the mixed syrup and diluent from said chamber upon the release of pressure therein.

7. A beverage mixing device, comprising a mixing chamber, a pressure piston therein, means to normally position said piston at an innermost limit, a valve having branches and connected with the interior of said chamber, a conduit connecting a branch of said valve with a source of syrup, a conduit connecting another branch of said valve with a source of diluent under pressure, a normally open valve in the syrup conduit and a normally closed valve in the diluent conduit, means in said first-named valve to prevent the flow of syrup into said diluent conduit while flowing into said chamber, and to prevent the flow of said diluent into said syrup conduit while flowing into said chamber, means to limit the flow of syrup to a predetermined quantity within said chamber, a coin-actuated valve to release and permit the expulsion of said syrup and diluent, said piston being moved by the pressure upon the diluent and operative to force the mixed syrup and diluent from said chamber when the pressure therein is released, and a coin-actuated mechanism operative in sequence to close said normally open syrup-control valve and to open said normally closed diluent-control valve until said piston has moved a predetermined distance, and to then permit the closing of said diluent valve while said syrup valve remains closed, and the opening of said release valve.

8. A beverage mixing device, comprising a mixing chamber having an aperture, a piston therein, a coil spring to normally maintain said piston in its innermost position, a valve having branches and connected with the interior of said chamber, a conduit connecting a branch of said valve with a source of syrup, a conduit connecting another branch of said valve with a source of diluent under pressure, a normally open control valve in the syrup conduit and a normally closed control valve in the diluent conduit, means in said first-

named valve to seal said diluent conduit when said syrup conduit is connected with the interior of said chamber, and to seal said syrup conduit when said diluent conduit is connected with the interior of said chamber, a float within said chamber to close said aperture and limit the quantity of syrup in said chamber, a valve to release and permit the expulsion of said syrup and diluent, said piston being moved against the tension of said spring by the pressure upon said diluent, and operative to force the mixed syrup and diluent from said chamber upon the release of pressure therein, and a coin-actuated mechanism operative in sequence to close said normally open syrup-control valve and to open said normally closed diluent-control valve until said piston has moved a predetermined distance, and to then permit the closing of said diluent valve while said syrup valve remains closed, and the opening of said release valve.

9. A beverage mixing and dispensing device, comprising a cabinet having an aperture, a door normally closing said aperture, a latch normally engaging said door and adapted to support a receptacle, means to regulate the automatic measuring and mixing of beverage ingredients, means to release a receptacle to rest upon said latch, and means to permit the mixed beverage to fill the receptacle to predetermined weight, said weighted receptacle being operative to actuate said latch to release said door, to permit its being opened and thereby permit access 35 to said receptacle for removing it from said latch.

10. A beverage mixing and dispensing device, comprising a cabinet having an aperture, a door normally closing said aperture, a latch normally engaging said door and adapted to support a receptacle, coin-controlled means to regulate the automatic measuring and mixing of beverage ingredients, means also coin-controlled to release a receptacle to rest upon said latch, and coin-controlled means to permit the mixed beverage to fill the receptacle to predetermined weight, said weighted receptacle being operative to actuate said latch to release said door, to permit 50 its being opened and thereby permit access to said receptacle for removing it from said latch.

11. A beverage mixing and dispensing device, comprising a source of syrup and a source of diluent under pressure, a mixing chamber, a syrup-regulating valve, a diluent-regulating valve, a valve to regulate the discharge of syrup and diluent from said chamber, and coin-controlled mechanism operative to actuate said first two valves in sequence to permit the flow of diluent into said chamber after syrup has flowed thereinto, and operative to then actuate said discharge 65 valve to permit the ejection of mixed syrup

and diluent from said chamber, and to then reset the device.

12. A beverage mixing and dispensing device, comprising a source of syrup and a source of diluent under pressure, a mixing chamber, a syrup-regulating valve, a diluent-regulating valve, a valve to regulate the discharge of syrup and diluent from said chamber, coin-controlled mechanism operative to actuate said first two valves in sequence to 70 permit the flow of diluent into said chamber after syrup has flowed thereinto, and operative to then actuate said discharge valve to permit the ejection of mixed syrup and diluent from said chamber, and to then reset 75 the device, a receptacle magazine, and means to release a receptacle from said magazine, said means being also actuated by said coin-controlled mechanism.

13. A beverage mixing and dispensing device, comprising a source of syrup and a source of diluent under pressure, a mixing chamber, a syrup-regulating valve, a diluent-regulating valve, a valve to regulate the discharge of syrup and diluent from said chamber, coin-controlled mechanism operative to actuate said first two valves in sequence to 80 permit the flow of diluent into said chamber after syrup has flowed thereinto, and operative to then actuate said discharge valve to permit the ejection of mixed syrup and diluent from said chamber, and to then reset 85 the device, a cabinet inclosing said device and having an aperture, a door normally closing 90 said aperture, a latch securing said door, a receptacle magazine, and means to release a receptacle from said magazine to rest upon said latch, said means being also actuated by said coin-controlled mechanism.

14. A beverage mixing and dispensing device, comprising a cabinet having an aperture, and within said cabinet a mixing cylinder, a spring-pressed piston within said cylinder, syrup and diluent-under-pressure conduits leading into said chamber, a valve in each of said conduits, a discharge valve leading from said cylinder to permit mixed beverage to flow into a receptacle, a rod extending from said piston outside of said cylinder, in combination with a sequential control mechanism comprising a pivoted lever normally on one position, a trigger release to permit said lever to fall into another position, a rod connecting said lever with said diluent valve to open it, means to arrest the rise of said lever, and a rod adapted to cooperate with said lever in its up-stroke to close said syrup valve and open said discharge valve, said piston rod in moving under the force of 100 said diluent under pressure being operative to release said arresting means to permit said lever to rise and in so doing to close said diluent valve, and permit said piston to eject 105 the mixed syrup and diluent from said cylinder, 110

der, into the receptacle for removal through said cabinet aperture.

15. A beverage mixing and dispensing device, comprising a cabinet having an aperture, a door closing said aperture, a latch normally securing said door and adapted to support a receptacle, a receptacle magazine, means to release a receptacle from said magazine to rest upon said latch, a mixing cylinder, 10 a spring-pressed piston within said cylinder, syrup and diluent-under-pressure conduits leading into said chamber, a valve in each of said conduits, a discharge valve leading from said cylinder towards the position of a receptacle upon said latch, a piston rod extending from said cylinder, in combination with a sequential control mechanism comprising a pivoted lever normally in a given position, a trigger release to permit said lever to move 15 into another position, a rod connecting said lever with said diluent valve to open it, means to arrest the return of said lever, and a rod adapted to cooperate with said lever in its return to normal position to close said syrup 20 valve and open said discharge valve, said piston rod in moving under the force of said diluent being operative to release said arresting means to permit said lever to return to normal position and in so doing to close said 25 diluent valve, and permit the piston to eject the mixed syrup and diluent from said cylinder, said piston rod in its outward motion having automatically actuated said receptacle releasing means.

30 35 In testimony whereof we have affixed our signatures.

THOMAS S. PATTERSON.
PETER G. PRITZ.
